UNITED STATES PATENT OFFICE.

HOWARD KENYON, OF HOUSTON, TEXAS.

LIFTING AND MOVING DEVICE.

1,170,757.

Specification of Letters Patent.

Patented Feb. 8, 1916.

Application filed February 20, 1915. Serial No. 9,522.

To all whom it may concern:

Be it known that I, HOWARD KENYON, a citizen of the United States, residing at Houston, in the county of Harris and State of Texas, have invented certain new and useful Improvements in Lifting and Moving Devices, of which the following is a specification.

This invention relates to new and useful improvements in a lifting and moving device.

The object of the invention is to provide a device of the character described specially adapted for the purpose of sustaining the weight of and moving heavy machinery, such as ditching machines, over marshy or soft earth, but may also be used for carrying any kind of heavy objects.

A further object of the invention resides in the provision of a device of the character described consisting of a frame work normally supported upon carrier wheels, and embodying also supporting runners, vertically movable relative to the frame work, which may be withdrawn from contact with the surface of the ground when the machine is passing over firm ground, but when soft or unstable earth is encountered, may be lowered relative to the frame work so as to lift said frame work and wheels and sustain the entire weight of the load.

With the above and other objects in view, the invention has particular relation to certain novel features of construction, operation and arrangement of parts, an example of which is given in this specification and illustrated in the accompanying drawings wherein:

Figure 1, is a side elevation of the device, showing the runners lowered, so as to contact with the ground surface, at one end: Fig. 2, shows a side elevation thereof, with the runners lowered so as to lift the rear wheels and the portion of the frame work sustaining the main load. Fig. 3, shows an enlarged side elevation of one of the lifting devices. Fig. 4, shows a vertical sectional view thereof. Fig. 5, shows a rear view of the device, as sustained by the wheels. Fig. 6, shows a transverse sectional view, taken on the line *a—a* of Fig. 2, and showing the load being sustained by the runners. Fig. 7, shows a plan view of the device. Fig. 8, shows a sectional view, illustrating the methods of securing the drums employed, to the traction wheels, and, Fig. 9, shows a

sectional view of the lifting device, taken on the line *b—b* of Fig. 3.

Referring now more particularly to the drawings, wherein like numerals of reference designate similar parts in each of the figures, the numerals 1, 1, refer to the side members of the supporting frame work, which are preferably formed of I beams, connected at their front ends by a suitable cross beam 2. The side members carry, respectively, alined bearings 3, 3, fixed to the rear ends thereof and in which the respective ends of the rear axle 4, rotate. This axle has traction wheels 5, 5, fixed thereon suitably spaced apart and located between the side members, and the cross beam 2, has a centrally located forwardly extending bearing member 6, having a vertically extending bearing, through which the shaft 7, extends. Fixed to the lower end of this shaft is the bearing member 8, having a transverse socket in which the front axle 9, rotates, and fixed to the respective ends of this axle are the guide wheels, 10, 10. Side runners 11, 11, are provided, which extend substantially the entire length of the frame work and are arranged on each side thereof, and have both their front and rear ends upturned as shown in Figs. 1 and 2. Each runner is formed of a bottom plate 12, upon which is mounted a plurality of I beams 13, 13, 13, which are fixed to said plate, suitably spaced apart and are of equal length therewith having their front and rear ends upturned to conform to the shape of the plate. Mounted upon these runners between the traction and guide wheels and secured thereto and suitably spaced apart, are suitable supporting plates 14, 14, 14, said plates of one runner being in alinement with the corresponding plates of the other runner, and fixed to each plate in transverse alinement are the bearing members 15, 15, having internally threaded sockets therein, threaded into which are the lower ends of the exteriorly threaded vertically extending shafts 16, 16. Three pairs of cross I beams 17, 17, 17, are provided, the beams of each pair being connected by bridges, as 18, each of which has a vertical bearing to receive the corresponding shaft 16. Each of said shafts 16, is enlarged above and below its corresponding bridge 18, forming the bearing heads 19 and 20, which hold each bridge in a fixed position, relative to the corre-

sponding shaft. The respective bridges 18, support, the corresponding ends of the cross I beams 17, which in turn support the side members 1, 1, and the respective ends of the pairs of cross I beams 17, are secured against lateral displacement by means of the braces 21, 21, fixed on the corresponding plates 14, on each side, of said pairs.

Fixed upon the rear axle 4, outside of the traction wheels 5, 5, are the respective drums 22, 22, having circular end plates, the inner end plate of each drum is secured to the spokes of the corresponding traction wheels by U bolts, as 23, which are secured to said plates and pass around said spokes. Cables, as 24, 24, have one end wound around these drums and the cables pass rearwardly between pairs 25, 25, of pulleys, rotatably mounted on the cross brace 26, connecting the rear ends of the runners, and the other ends of these cables may be attached to a suitable stationary object.

When the machine is passing over firm ground the wheels thereof are in contact with the surface, the runners being elevated. When soft or marshy earth is encountered a bar or some other suitable implement, is inserted through the orifice 27, extending transverse through the upper end of each shaft 16, and the shafts are successively turned, so as to lower the runners until they contact with the surface of the ground and the operation is continued until the wheels are lifted clear of the ground, and the runners having a wide under surface will support the entire load without sinking into the earth.

The device herein described is particularly adapted to be used for supporting a ditching mechanism known as the drag-line ditcher, and the complete device is in constant movement along the line of the ditch, as the excavation proceeds. While the runners are being employed to support and transport the device, a suitable engine (not shown) is in operative connection with the traction wheel shaft 4, and so geared therewith as to impart a slow rotation thereto which operates to wind the cables 24, 24, around the drums to which the cables are attached.

The excavation bucket employed in the operation of the ditcher is suspended from a boom; and in order to discharge the load the boom and bucket are swung around to the side of the machine and the bucket there emptied. The weight of the loaded bucket has a tendency to cause the machine to tip over and were it not for the side runners, spuds or side braces would have to be employed to prevent the machine from capsizing. When the machine is on firm ground, the front ends of the side runners may be lowered into contact with the surface of the ground, as shown in Fig. 1, and they

will act as braces to prevent the turning over of the machine; and the cross braces 17, may be of any desired length, according to the length of the boom employed. When the machine is being sustained entirely upon the side runners they form a wide supporting base and prevent the overturning of the machine in operation.

While I have shown only one form of this device, it is obvious that the mechanical structure thereof may be varied without departing from the principle of the invention, and I hereby reserve the right to make such changes therein as may be found necessary so long as I keep within the scope of the appended claims.

What I claim is:

1. A device of the character described including a frame-work consisting of side-members and cross beams arranged in pairs and secured to said side-members, a pair of runners, upstanding braces arranged in pairs and fixed to the runners, the ends of the respective pairs of cross-beams being arranged between the members of the corresponding pairs of braces, bridges connecting said pairs of beams at their respective ends, bearing members having internally threaded sockets fixed to said runners underneath the respective bridges, vertical shafts threaded into said sockets and whose upper ends support the respective bridges and by the manipulation of which said bridges and the frame-work supported thereby may be raised and lowered.

2. A device of the character described including a frame-work mounted upon carrier wheels and consisting of side members and cross beams arranged in pairs and secured to said side members, a pair of runners, upstanding braces arranged in pairs and fixed to the runners, the ends of the respective pairs of cross-beams being arranged between the members of the corresponding pairs of braces, bridges secured to said pairs of beams at their respective ends, bearing members having internally threaded sockets fixed to said runners underneath the respective bridges, vertical shafts threaded into said sockets and whose upper ends support the respective bridges and by the manipulation of which said bridges and the frame-work supported thereby may be raised and lowered, relative to said runners.

3. A device of the character described including a frame-work mounted upon carrier-wheels and consisting of side-members and cross-beams secured thereto, a pair of runners, upstanding braces arranged in pairs and fixed to the runners, the ends of the cross-beams being arranged between the members of the corresponding pairs of braces, bridges secured to said beams at their respective ends, bearing members having internal threaded sockets fixed to the said run-

ners underneath the respective bridges, vertical shafts threaded into said sockets and whose upper ends have swivel-connections with the respective bridges and by the manipulation of which the frame-work and runners may be elevated and lowered relative to each other.

Copies of this patent may be obtained for five cents each, by addressing the "Commissioner of Patents, Washington, D. C."

In testimony whereof I have signed my name to this specification in the presence of two subscribing witnesses.

HOWARD KENYON.
